CARD CASE

Forest H. Hartzell, Dayton, Ohio

Application May 28, 1934, Serial No. 727,946
Renewed November 12, 1936

24 Claims. (Cl. 206—39)

This invention relates to card cases for business cards and the like and more particularly to a card dispensing holder from which the cards may be successively ejected one at a time.

Whereas heretofore card dispensing devices have been of bulky size, rigid construction and of too heavy weight to be conveniently carried in one's pocket, the present card dispensing holder is preferably a folder of leather or the like of flexible or collapsible character, convenient form and weight, good appearance and adapted to assure ejection of a card at each operation.

The object of the invention is to improve the construction as well as the means and mode of operation of card dispensing devices whereby they may not only be economically manufactured, but will be more efficient in use, capable of being easily operated, positive in action, of relatively few parts and unlikely to get out of repair.

A further object of the invention is to provide a flexible folder type of card holder equipped with card ejector means.

A further object of the invention is to provide means for automatically disposing the card supply in a staggered or echelon relation whereby the ejector device may more readily engage a card at each operation.

A further object of the invention is to provide an improved card retaining and guiding means.

A further object of the invention is to provide an improved ejector slide therefor.

A further object of the invention is to provide an improved tensioning leaf for maintaining the cards under pressure.

A further object of the invention is the concealment of the slots through which the ejector slide operates.

A further object of the invention is the provision of secure but economical means and method for interconnecting the various parts.

With the above primary and other incidental objects in view, as will more fully appear in the specification, the invention consists of the features of construction, the parts and combinations thereof, and the mode of operation, or their equivalents, as hereinafter described and set forth in the claims.

In the drawing wherein is shown the preferred, but obviously not necessarily the only form of embodiment of the invention, Fig. 1 is a perspective view of the assembled card dispensing device forming the subject matter hereof in closed condition. Fig. 2 is a perspective view of

the card dispensing device in unfolded or extended condition. Fig. 3 is a longitudinal sectional view. Fig. 4 is a transverse sectional view. Fig. 5 is a disassembled view of component parts of the device. Figs. 6 and 7 are detail views.

Like parts are indicated by similar characters of reference throughout the several views.

The present card holder and dispensing device comprises a folder of leather or other flexible material having therein a metallic trough-like guide and retainer for the cards upon which is mounted an ejector slide. One of the inturned flaps of the folder forms a yielding abutment for one end of the stack of cards which due to the inclined relation of the folder flap are disposed in offset or staggered relation whereby the ejector slide may more readily engage the protruding edges of the cards singly. The leather flap yieldingly permits the ejector slide to be retracted beyond the end of the card to be engaged. A separate curved spring plate which forms a yielding side for the retainer interiorly of the folder, bears upon the opposite terminal portions of the cards to press the initial card of the series into the path of the ejector slide and also into the plane of a discharge slot through which the card is ejected from the holder. The ejector slide is actuated by a sliding button accessible exteriorly of the folder and connected with the ejector through slots which are concealed beneath an escutcheon.

Referring to the drawing, 1 is a flexible folder of leather or the like which includes the end flap 2 and the side flaps 3—3 to be folded into overlapping relation and secured by a snap fastener 4 or other fastening device over the terminal flap 2, which extends interiorly of such side flaps. The folder is provided with an opening 5 in one side to afford access to the ejector slide button, which opening is surrounded and its margin overlaid by an escutcheon plate 6 which may be highly ornamental, embossed or of fret work design. The escutcheon illustrated is of quite plain and simple design.

Secured interiorly of the folder 1 to the side thereof carrying the escutcheon 6 is a metallic stiffening and guide plate 7 preferably of thin light alloy such as duraluminum or the like. The side margins of the guide plate are upturned at 8 in conformity with the width of the cards and their edges are inwardly flanged at 9 in slightly overhanging relation with the pack of cards 10. At one end of the guide plate the upstanding side walls are beveled as at 11. The stiffening and guide plate 7 with its upstanding inwardly

45

50

55

flanged sides 8 forms a substantially trough-shaped receptacle for the pack of cards 10. This trough-like receptacle is entirely open on one side and at one end. At the opposite end the 5 guide plate carries an angular abutment head 12 one wall of which extends perpendicular to the plane of the guide plate 7 but is spaced away therefrom sufficiently to afford a discharge slot 13 for the card to be ejected, while the other wall 10 of the head 12 overhangs the end of the card pack in parallel relation with the plate 7. The more popular business cards have thickness of six, eight, or ten thousandths of an inch. The discharge slot 13 intermediate the head 12 and plate 15 7 is preferably ten thousandths of an inch wide so that it will permit the passage of a card of the greatest thickness but will not permit the simultaneous passage of two cards of the least thickness. These dimensions are mentioned only 20 for illustrative purposes and with no intent nor purpose of unduly limiting the invention nor confining it to any particular dimensions, thickness or character of cards. It is to be understood that the device may be made in various 25 sizes for tickets, checks or cards of thickness other than those mentioned.

The abutment head 12 is located in such relation with the end of the guide plate or retainer 7 that the plate projects slightly beyond the head 12 and discharge slot affording a narrow projecting ledge 14 which has been found quite advantageous. The stiffening and guide plate 7 is provided with parallel spaced slots 15 separated slightly more than the width of the access opening 5 in the folder, whereby the slots will be positioned beneath the escutcheon plate 6 and concealed thereby. The escutcheon plate is riveted or otherwise secured to the guide plate 7 with the folder material contiguous to the margin of the 40 opening 5 clamped therebetween. The preferable mode of attachment is by welding, soldering or otherwise attaching to the under side of the escutcheon plate 6 thin strips 16 of metal having extruded eyelets 17 to be projected through corresponding holes in the folder material and thence through registering holes 18 in the guide plate 7 where the ends of the extrusions 17 are expanded or clenched, preferably by a spinning or staking operation. The holes 18 are preferably countersunk to receive the upset ends of the extrusions substantially flush with the guide plate 7.

Slidably mounted upon the inner face of the stiffening and guide plate 7 for reciprocatory motion is an ejector plate 20, the rear edge of which is slightly upturned at 21 to the extent of the thickness of the thinnest card or ticket to be dispensed. This is best achieved by flanging the ejector slide at substantially right angle to the 60 plane thereof and temporarily applying in the flange angle a gage plate substantially equal to the thickness of the thinnest card, usually about six thousandths of an inch, and then shearing the upturned flange 21 flush with such plate.

The reciprocatory ejector plate 20 is provided with two extruded projections or eyelets 22 spaced to correspond with the parallel slots 15 through which they extend into engagement with the movable operating button 23 located within the 70 opening 5. The operating button is formed with lateral extensions 24 which project beneath the escutcheon plate and underlying folder material at opposite sides of the opening 5. The button extensions 24 are also provided with extruded projections or eyelets 25 registering with

the extrusions 22 of the ejector plate. The extrusions or eyelets of one member are of sufficient size to be received within those of the other member as illustrated in detail in Fig. 6, whereby the exterior or enclosing extrusions or eyelets act as spacers to maintain the ejector plate and operator button sufficiently spaced when interconnected to prevent binding and to enable them to slide freely to and fro relative to the plate 7 through the spaced slots 15 of which they are interconnected. The inner set of the telescoped extrusions or eyelets are expanded or upset to firmly and positively secure the parts together through the slots 15. Overlying the pack of cards 10 to be dispensed, is an independent curved spring 15 plate 26 substantially the same size as the cards. The tension plate 26 engages beneath the in-turned flanges 9 by which it is confined with its concave side toward the cards. Its ends are slightly deflected as at 27 so that when the 20 supply of cards is exhausted the plate cannot be engaged by the ejector slide which will pass freely thereunder, nor be projected through the outlet slot 13. The curved spring plate 26 is free for removal from the assembly, and when in 25 position it exerts pressure on the end portions of the card pack to press one end of the underlying card into the plane of the discharge slot 13 and the other end into the path of the upturned flange 21 of the ejector slide 20. The 30 ejector plate 20 and the guide slots 15 are of such length that when the ejector plate is fully retracted its flanged rear margin will project slightly beyond the rear margin of the guide plate 7 where it abuts upon the yielding flexible terminal flap 2 of the folder, slightly beyond the 35 end of the lowermost card of the pack. Thus the flexible terminal flap 2 forms a yielding abutment or stop for the ejector slide. When the terminal flap 2 is infolded over the card pack 40 it tends to assume an inclined relation and distorts the stack or pack of cards 10 into staggered, stepped or echelon relation wherein the lowermost card or ticket, or that to be next ejected, projects farthest rearwardly. As the ejector 45 slide moves rearwardly the flap 2 will yield sufficiently to enable the ejecting flange 21 to pass beyond the edge of the card. It is found that positive engagement of the ejector slide with the card is assured by the retraction of this engaging edge of the ejector slide slightly beyond the 50 terminal margin of the plate 7. Upon advancement of the slide 20 from such rearward engaging position the engaged card is ejected through the discharge slot 13, as is illustrated in Fig. 1, 55 a distance sufficient to enable it to be grasped and manually withdrawn therefrom.

The folder is quite flexible and is collapsible against the yielding tension of the spring plate 26, its bulk diminishing with the supply of cards. 60 Being non-rigid and having minimum parts it is quite light in weight and possesses a comfortable feel in the operator's hand, quite different from the usual rigid, heavy metallic box-type of card holders.

The ejector slide 20 is of such width as to fit between the upstanding sides of the reinforcement and guide plate 7 with a free sliding fit at its opposite edges. This marginal bearing of the slide in connection with the parallel slots 15 70 serves to keep the slide aligned and its engaging edge parallel with that of the card to be ejected. The slide 20 is preferably, although not necessarily, long enough to entirely cover and conceal the slots 15 from the interior of the reinforce- 75

ment and guide unit 7, while said slots are covered and concealed from the outside by the escutcheon plate 6 and interposed envelope material.

5 The terminal flap 2 is preferably formed as a separate piece and stitched to the envelope portion 1 in an inturned position with the joined edges substantially flush in overlying relation. By so attaching the flap 2 the case will present 10 a better appearance and there will be no bulging of the end, and further the flap will be inclined to the plane of the case and so tend to confine the stack of cards in a staggered or offset relation.

Whereas prior card cases have usually been of 15 rigid construction which when subjected to pressure in one's pocket are liable to be crushed or bent and so interfere with the smooth operation of the ejector, the present case is sufficiently flexible and yielding that it will not be damaged by 20 any ordinary pressure. The overhang or extension of the guide plate 7 beyond the abutment head 12 and discharge slot 13 thus forming the ledge 14, affords a stop for the head 12 when the case is subjected to extreme pressure which otherwise might force the front wall of the abutment head 12 past the end of the guide plate 7 where these parts might become locked or distorted to such extent as to close the discharge slot 13 and prevent ejection of the card.

25 30 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the 40 invention has been described in language more or less specific as to structural features, it is to be understood that the invention is not limited to the specific features shown, but that the means and construction herein disclosed comprise the 45 preferred form of several modes of putting the invention into effect, and the invention is therefore claimed in any of its forms or modifications within the legitimate and valid scope of the appended claims.

50 Having thus described my invention, I claim:

1. In a card dispensing device, a flexible folder 55 for enclosing a pack of cards, a stiffening and guide plate secured to one side of the folder interiorly thereof, a reciprocatory ejector slide mounted on the guide plate, an abutment head for the card pack in spaced relation with the guide plate to afford therebetween a discharge slot, said folder having an access opening, an escutcheon plate surrounding the opening, an 60 operator button movable within the access opening, extensions thereon projecting beneath the escutcheon plate and there interconnected with the ejector slide, and a yielding abutment for the card pack engaged by the ejector slide in 65 its retractive movement to facilitate engagement with a card to be ejected.

2. A card dispensing device including a flexible 70 folder for enclosing a pack of cards to be dispensed, a stiffening and guide plate secured within the folder, a reciprocatory ejector slide mounted thereon, an abutment for confining the card pack there being a slot for discharge of the cards one by one and an operator button 75 connected with the ejector slide and operable

from the exterior of the folder to reciprocate the ejector slide.

3. A card dispensing device including a flexible folder for enclosing a pack of cards to be dispensed, a spring member within the folder and bearing upon the pack of cards, said spring member being subject to manual tension by compression of the flexible folder, card ejector means interiorly of the folder for ejecting cards therefrom one at a time, and means operable from the exterior of the folder for actuating the ejector means.

4. In a card dispensing device, a flexible leather folder for enclosing a pack of cards to be dispensed, including a terminal flap to be inturned over the card pack, a reciprocatory card ejector means interiorly of the folder for ejecting the cards one at a time, actuating means for operating the ejector slide from the exterior of the folder, said ejector means having a yielding engagement with the terminal flap upon retraction thereof to facilitate its engagement with a card to be dispensed.

5. In a card dispensing device, a flexible folder for enclosing a pack of cards to be dispensed including overlapping side flaps and an end flap to be enclosed therebeneath, a guide plate located interiorly of the folder extending into proximate relation with a discharge outlet, a reciprocatory ejector slide mounted on the guide plate, and an operator device for the ejector accessible from the exterior of the folder.

6. In a card dispensing device, a flexible folder for enclosing a pack of cards to be dispensed including overlapping detachably engageable side flaps and an end flap to be enclosed beneath the side flaps, said flaps being of yielding character thereby permitting pressure externally applied to the folder to be transmitted to the enclosed pack of cards for urging a card of such pack into position to be ejected from the folder, card ejector means enclosed within the flexible folder and actuating means therefor accessible from the exterior of the folder for discharging the cards one at a time from said folder through an outlet slot.

7. In a card dispensing device a collapsible container of flexible material to enclose a pack of cards to be dispensed, and having an outlet opening for discharge of cards, card ejector means enclosed within the container for ejecting cards therefrom one at a time, and actuating means accessible from the exterior of the container for operating the card ejector means.

8. A card dispensing device including a receiver for a pack of cards to be dispensed having a card ejector opening, means for disposing the card pack in echelon within the receiver whereby the card next to be dispensed will project rearwardly away from the ejector opening beyond other cards of the pack, means for exerting pressure upon the card pack within the receiver for urging a card of the pack into position for ejection from the receiver, and a reciprocatory card ejector engageable with the edge of the card projecting farthest from the pack.

9. In a card dispensing device a container for a pack of cards to be dispensed, a reciprocatory ejector for discharging the cards from the container one at a time, and a yielding abutment engaged by the reciprocatory ejector upon its retrograde movement and subject to displacement thereby to permit the ejector to pass be-

yond the limit of the card pack to enable its engagement with a card thereof.

5 10. In a card dispensing device, a container for a pack of cards to be dispensed, a reciprocatory ejector for discharging the cards therefrom one at a time, and a yielding end wall for the container confining the cards but yielding to the retrograde movement of the ejector to permit the ejector to be retracted beyond the rearmost card 10 of the pack.

10 11. In a card dispensing device, a container for a pack of cards to be dispensed having a discharge opening through which the cards are to be ejected, a reciprocatory ejector for discharging the cards therefrom one at a time, and inclined means disposing the card pack in eche- 15 lon whereby the card next to be ejected will project farthest from the discharge opening into the path of the reciprocatory ejector for en- 20 gagement thereby.

15 12. In a card dispensing device a guide plate, upstanding side walls therefor and an abutment head disposed in spaced relation with the guide plate to afford a discharge slot therebetween, the 25 side walls being inwardly flanged, said structure being open at its top and at one end, a reciprocatory ejector mounted on the guide plate, and an independent curved spring plate removably engaged beneath the flanges of the side walls 30 forming a yielding closure for the open top of the guide plate structure and exerting pressure on opposite terminal portions of the card pack.

35 13. In a card dispensing device, a receptacle for a pack of cards to be dispensed having an open side, inwardly projecting flanges contiguous to the open side of the receptacle, a reciprocatory ejector for discharging the cards therefrom one at a time, and a spring pressure plate independent of the receptacle removably positioned therein beneath said inwardly projecting flanges, said plate being of substantially the full width of the cards to be dispensed and bent into arcuate form and engageable with the card pack with its concave side adjacent thereto and abut- 40 ting its convex side against said flanges, the pack engaging ends of the plate being slightly bent in reverse direction away from the card pack.

45 14. In a card dispensing device, a receptacle for a pack of cards to be dispensed, having a discharge outlet therefrom, said receptacle being open at one side and inwardly flanged at said open side, traveling card ejector means within the receptacle and operable from the exterior thereof, and a curved spring pressure plate independent of the receptacle removably engageable in the open side thereof beneath its inward flanges, said plate bearing upon the opposite terminal portions of the card pack and pressing one end of the next card to be ejected into the 60 plane of the discharge outlet and the opposite end of said card into the path of travel of the ejector, said spring plate forming a yielding removable side wall for the receptacle.

65 15. In a card dispensing device, a container for a pack of cards to be dispensed, a reciprocatory ejector slide therein, a movable actuating button exteriorly of the container for reciprocating the ejector slide, an escutcheon plate upon the container having an opening within which the button is operable, extensions upon the actuating button projecting beneath the escutcheon plate, said container having slots therein located beneath the escutcheon plate through which the ejector slide is connected with the button ex- 70 tensions, whereby the slots and interconnections 75

of the button extensions with the ejector slide are concealed.

5 16. In a card dispensing device, a container for a pack of cards to be dispensed, a reciprocatory ejector slide therein, an actuating button for the slide exteriorly of the container and operatively connected therewith through a slot in the container, and an escutcheon plate upon the exterior of the container concealing the said slot and the interconnection of the button with the slide.

10 17. In a card dispensing device, a container for a pack of cards to be dispensed, a reciprocatory ejector slide therein, an actuating button for the slide exteriorly of the container and operatively connected therewith, an escutcheon plate exteriorly of the container having an opening therein within which the button is movable, said container having spaced parallel slots therein located beneath the escutcheon plate beyond the limits of said opening, extensions on said button projecting beneath the escutcheon plate and interconnections between the button extensions and the ejector slide through said slots, the slots and extensions being concealed from view by the escutcheon.

15 18. In a card dispensing device, a receiver for a pack of cards to be dispensed, a reciprocatory ejector slide within the pack receiver, an actuating button therefor, said container having a slot therein through which the ejector slide and button are interconnected, an integral extruded eyelet on one of said members projecting through said slot into engagement in a corresponding hole in the other member to fixedly interconnect the ejector slide and the actuating button interiorly and exteriorly respectively of the pack receiver.

20 19. In a card dispensing device, a receiver for a pack of cards to be dispensed, a reciprocatory ejector slide within the pack receiver, an actuating button therefor, said container having a slot therein through which the ejector slide and button are interconnected, integral extruded eyelets on both of said members projecting through said slot, one enclosed within the other, whereby the outer extruded eyelet limits the approach of the button and slide toward each other and the inner extruded eyelet interconnects said members one with the other for unison movement.

25 20. In a card dispensing device, a receiver for a pack of cards to be dispensed, a reciprocatory ejector slide within the pack receiver, an actuating button therefor, said container having a slot therein through which the ejector slide and button are interconnected, an escutcheon carried by the receiver and having an opening therein with- 30 in which the button is movable, and a flexible cover for the pack receiver having a correspond- 35 ing opening therein, the margin of which is clamped between said escutcheon and the pack receiver.

40 21. In a dispensing device for cards, a unitary container for a pack of cards having a discharge slot at one end thereof and including a substantially rigid wall contiguous thereto adapted to guide a card to the discharge slot, ejector means for discharging cards one at a time through the slot, and a yielding wall for said container opposite said rigid wall confining the cards within the container therebetween and subject to external pressure by which the cards are pressed 45 toward such rigid guide wall into position for successive discharge thereof.

45 22. In a dispensing device for cards, a container for a pack of cards having a discharge outlet, ejector means for ejecting the cards one at a 50

time therefrom, and a yielding cover for said pack of cards subject to manual pressure by the operator for urging the cards successively into position for ejection from the container.

5 23. In a dispensing device for cards, a collapsible enclosure for a pack of cards within which the cards may be subjected to manual pressure by the operator, said enclosure having a discharge opening through which the cards 10 may be ejected one by one, and ejector means within the enclosure for ejecting said cards singly through said opening.

24. A dispensing device for cards including a unitary container for a pack of cards having a discharge slot at one end thereof, ejector means associated therewith for ejecting the cards one at a time through said opening, and a depressible 5 removable cover for said container subject to manual pressure by the operator for urging the cards of the pack successively into position for discharge through the said slot by the ejector means. 10

FOREST H. HARTZELL.
